Professional Association(57) **CLAIM**

The ornamental design for a one handed dispenser for container, substantially as shown and described.

DESCRIPTION

FIG. 1 is a front perspective view of a one handed dispenser for container affixed to a pouch in accordance with the present invention;

FIG. 2 is a top plan view of the one handed dispenser for container of FIG. 1;

FIG. 3 is a front elevation view of the one handed dispenser for container affixed to a pouch of FIG. 1; and,

FIG. 4 is a right side elevation view of the one handed dispenser for container of FIG. 1.

In the drawings, the broken lines show portions of a one handed dispenser for container that form no part of the claim.
